UNITED STATES PATENT OFFICE.

ELLSWORTH L. McCAIN, OF DETROIT, MICHIGAN.

SAFETY-RAZOR.

1,103,904.

Specification of Letters Patent. Patented July 14, 1914.

Application filed April 28, 1913. Serial No. 764,054.

To all whom it may concern:

Be it known that I, ELLSWORTH L. McCAIN, a citizen of the United States of America, residing at Detroit, in the county 5 of Wayne and State of Michigan, have invented certain new and useful Improvements in Safety-Razors, of which the following is a specification, reference being had therein to the accompanying drawings.

10 This invention relates to safety razors, and the object of my invention is to provide a razor embodying a guard plate, a clamping plate, blades, and means between the plates for holding the blades at a proper inclination and against accidental displacement.

The invention consists in matters herein-after set forth and particularly pointed out in the appended claim.

20 In the drawings, Figure 1 is a cross sectional view of a portion of a razor; Fig. 2 is a plan of a pair of single edge blades; Fig. 3 is a perspective view of the clamping plate, and Fig. 4 is a similar view of a 25 guard plate.

In the drawing, the reference numeral 8 denotes a portion of a stem or handle having the outer end thereof provided with a shoulder or flange 9, which affords a seat for a 30 guard plate 11. The guard plate 11 has beveled, serrated or toothed longitudinal margins 14 and guide pins or lugs 15 that are tapered and have their greatest diameter at said plate. The guide pins are adapted to 35 enter corresponding recesses 16 in a clamping plate 13. This plate is slightly crowned or cambered so as to bear along its longitudinal margins on the guard plate or on blades 21 placed between said plates. The 40 blades 21 are made of thin metal and are proportioned to rest on the guard plate with the cutting edges 18 thereof in operatable relation to the serrated margins 14 of the guard plate, said blades having guide openings 19 for the guide pins 15 and cut away inner edges 20 providing clearance for the 45 extreme end of the stem 8. The extreme end

of the stem 8 is screw threaded and is adapted to enter a socket 12 in the clamping plate 13, whereby the two plates will be retained upon the end of the stem. 50

The blades 21 are maintained at an inclination with respect to the flat guard plate 11 by the sides of the tapering guide pins 15; the openings 19 of the blades being of less 55 diameter than the base of each pin. In consequence of this construction, the blades can be tilted at a proper inclination to be held in operative position by the clamping plate relative to the beveled toothed edges of the 60 flat guard plate. It is therefore apparent that the pins 15 perform a function that is necessary in order that the blades can be correctly positioned.

What I claim is:

65 A safety razor comprising a flat guard plate, a supporting stem, tapering guide pins carried by said plate adjacent to the longitudinal edges thereof, said guard plate having the longitudinal edges beveled and 70 toothed, blades having the inner edges thereof cut away to provide clearance for said stem and provided with apertures to receive said tapering pins, but of smaller diameter than that of the base of the pins, 75 whereby said blades can be supported by the sides of said pins at an inclination relative to said guard plate and with the beveled edges thereof in a plane with the beveled edges of said guard plate, and a clamping 80 plate in screw threaded engagement with the stem and recessed to receive the tapering guide pins and adapted to bear along the longitudinal margins of said blades and maintain the beveled edges thereof in a plane with 85 the beveled edges of said guard plate and said clamping plate.

In testimony whereof I affix my signature in presence of two witnesses.

ELLSWORTH L. McCAIN.
